(57) **CLAIM**

The ornamental design for a personal media player case, as shown and described.

DESCRIPTION

FIG. 1 is a perspective front view of a personal media player case according to the present invention.

FIG. 2 is an exploded, perspective front view of a personal media player case according to the present invention.

FIG. 3 is a rear view of a personal media player case according to the present invention.

FIG. 4 is an exploded, rear-perspective view of a personal media player case according to the present invention.

FIG. 5 is a top plan view of a personal media player case according to the present invention.

FIG. 6 is a bottom plan view of a personal media player case according to the present invention.

FIG. 7 is a left elevation view of a personal media player case according to the present invention; and,

FIG. 8 is a right elevation view of a personal media player case according to the present invention.

The portions of the drawings shown in broken lines are environmental structure and are not part of the design sought to be patented.
